UNITED STATES PATENT OFFICE

SILIAM BJORRE, OF SKIVE, DENMARK

QUERN

Application filed June 9, 1928. Serial No. 284,093.

The present invention relates to a quern of the kind comprising a rotary and a non-rotary grinding body between which the substance to be ground is introduced, the said 5 substance being, perhaps, grain, cacao, coffee or some other similar substance.

In querns of this nature it has previously been proposed to journal the grinding bodies in such a manner that excessive loading of 10 the quern will cause one of the grinding bodies to be displaced away from the other one.

This relative displacement of the grinding bodies is effected either by the material 15 to be ground between the grinding surfaces pushing the rotary grinding body away from the non-rotary grinding body and, at the same time, compressing a spring which holds the rotary grinding body in contact with the material to be ground, or by the friction between 20 the grinding bodies and the material to be ground, which friction is highly increased by overload on the quern and causes a rotation of the non-rotary grinding body, 25 whereby the latter moves axially away from the rotary grinding body. In the last mentioned case the rotation of the non-rotary grinding body has also been utilized to reduce the supply of material to the quern by 30 displacing the feeding device for the material to be ground.

These heretofore known querns, however, and the methods used for regulating the same suffer from various drawbacks. When the 35 relief of the quern during an overload is effected by displacement of the runner, this displacement as a rule causes compression of the spring pressing the runner against the material to be ground. This compression, however, increases the spring power and, consequently, the pressure at which the spring 40 presses the rotary grinding body against the material. If the overload is due for instance to a hard foreign body entering between the 45 grinding surfaces, then the displacement of the rotary grinding body will consequently cause the pressure between the said foreign body and the grinding surfaces to be increased, the consequence of which may be a total destruction of the grinding surfaces.

If the above mentioned rotation of the non-rotary grinding body is utilized to regulate the load, then the said body must be adapted to rotate as well as to be displaced in axial direction, and according to circumstances the 55 construction of the quern may consequently be complicated and expensive.

One of the objects of the present invention is to produce a quern by which, in case of overloading, a relief is effected automatically by an axial relative displacement of the two grinding bodies, without the pressure between the latter and the material being thereby increased, which advantage is attained by journaling the quern housing 60 in such a manner that the said housing, when the friction between the grinding bodies and the material to be ground exceeds a certain permissible value, is swung through a larger or smaller angle in the direction of rotation 65 of the quern shaft, whereby a displacement of the grinding surfaces relatively to one another is effected.

Another object of the invention is to utilize the said rotation of the quern housing 75 for reducing the supply of grain to the quern, the said reduction being attained by arranging a tappet on the quern housing to engage a shaking tray, which is kept in motion by means actuated by the quern shaft and which 80 serves to supply the material to the feeding aperture of the quern housing, and to push the said tray away from the said means.

A further object of the present invention is to employ means by which the distance between the grinding surfaces may be adjusted 85 to any desired extent, in such a manner that the degree of fineness obtained by the grinding treatment may always be determined at will.

Still another object of the invention is the provision of means by which the grinding bodies may be moved manually away from one another by a rotation of the quern housing by hand.

Finally the invention relates to means by which the quern housing is attached in such a manner to a frame in which it is journalled that the quern housing, when actuated by the friction between the grinding surfaces, 100

will not rotate until the load on the quern and, hence, the said friction, has exceeded a certain limit.

Still another object of the invention is the use of means by which the grinding bodies may be moved manually away from one another by a rotation of the quern housing by hand.

Further details of the invention will appear from the following description of the constructions shown on the drawing.

Fig. 1 is a central vertical section of a quern constructed according to the invention,

Fig. 2 is an end view of the quern, with parts in section, and

Fig. 3 is a section of the quern along the line B—B in Fig. 2,

Figs. 4 and 5 are views corresponding to Figs. 1 and 2, but showing another construction of the quern,

Figs. 6 and 7 represent a detail of the construction shown in Figs. 1 and 2, in cross-section and in longitudinal section, respectively, and

Fig. 8 is a diagrammatic view of another construction of the quern, in side elevation.

1 is a frame shaped as a hollow post, and 2 is a mainly cylindrical quern housing formed on one side with a projecting hollow trunnion 3 by which the housing 2, referred to in the following as the quern case, is journalled in the frame 1.

In the quern case there is fixed a mainly annular grinding body 4 with a central cavity 5 communicating with a feeding channel 6 on the quern case. 7 is a shaft which is journalled in the trunnion 3, in ball bearings 8 inserted in the same. One end of the shaft 7 extends into the quern case and supports there a grinding body 9 disposed opposite the grinding body 4. 10 is a helical spring inserted in the trunnion 3 so that it encircles a portion of the shaft 7 and exerts an axial resilient pressure on the latter, which pressure maintains the grinding body 9 in resilient contact with the material contained between the grinding bodies. One end of the spring 10 rests against one of the ball bearings 8 in which the shaft 7 is free to move axially, and the other end of the spring rests against an eccentric 11 which is fastened on said shaft and the function of which will be described more fully later on. 12 is a belt pulley fixed on the shaft 7 beyond the end of the trunnion 3 and serving to rotate the shaft 7 and the grinding body 9.

The material to be ground in the quern is introduced into a hopper 13 supported by brackets 14, Fig. 2, which are attached to the frame 1. The hopper 13 discharges at bottom into a so-called shaking tray 15, one end of which is pivoted about a pin 16 on the hopper, while the other end projects out to, and overlies, the feed channel 6 on the quern case.

17 is a rod which extends out through the hollow frame 1 and is guided at both ends by suitable holes in the same, one end of the said rod resting against the periphery of the eccentric disc 11, while the other end rests against the bottom of the shaking tray 15 as shown by Fig. 1.

On the end facing the quern, the channel 6 is fitted with an arcuate projection 18. Between the latter and a flange 19 on the bottom portion of the frame 1 there is inserted a resilient member consisting of a rod 20 the upper end of which is threaded and rests against the bottom side of the projection 18, while the lower end of the rod is adapted to slide in a conical guiding block 21, the bottom end of which is journalled in the flange 19 by means of a pin 22. Around the rod 20 and the guiding block 21 there is inserted a helical spring 23 the bottom end of which rests against a flange 24 on the guiding block 21 and the top end of which rests against a cupped washer 25 which is inserted on the top end of the rod 21 and is held in position against the pressure of the spring 20 by means of a nut 26. By tightening up this nut it becomes practicable, without altering the length of the entire device consisting of the rod 20, the spring 23 and the guiding block 21, to regulate the spring pressure and, thereby, the force with which the spring tends to turn the quern case in the direction indicated by the arrow in Fig. 2 which is opposite the direction of rotation of the grinding body 9. The tension of the spring 23 is adjusted in such a manner that the quern case will remain in the position shown in Fig. 2 as long as the quern is in use without being overloaded, since the power of the spring 23 will counter-balance the torsional moment due to the friction between the grinding bodies and tending to rotate the quern case in a direction opposite the direction of the arrow in Fig. 2.

The ball bearing 8 nearest to the rotary grinding body 9 rests on one side against the eccentric sleeve 11 and on the other side against a ring 27 inserted on the shaft 7, see Figs. 1 and 3. The side of the ring 27 facing the grinding body 9 rests against the slotted central portion 28 of an arm 29 which is disposed inside of a bore 30 on the side of the quern case facing the frame 1, and is attached to the quern case at both ends by means of a bolt 31, Fig. 3, which passes through the quern case and through a washer 32 disposed on the outside of the latter; a hand wheel 33, Fig. 3, being provided on the bolt 31 outside of the said washer. Both ends of the arm 29 are attached to the quern case in the above described manner, so that by tightening up the hand wheels 33, one of which is shown in Fig. 2 and the other one in Fig. 3, the central portion 28 of the arm 29 extending transversely through slots 34 in the trunnion 3, but outside of the shaft 7, 130

may be pressed more or less forcibly against the ring 27. Consequently the arm 29, together with the hand wheels 33 and the pin 31, may serve to adjust the distance between the grinding surfaces 35 and 36, respectively, on the two grinding bodies 4 and 9, since a rotation of the hand wheels 33 will cause a displacement of the ring 27 towards the spring 10 and, thereby, a compression of the latter simultaneously with an axial displacement of the shaft 7 and the grinding body 9 away from the grinding body 4. In this manner it becomes practicable, by adjustment of the hand wheels 33, to attain any desired distance between the grinding surfaces 35 and 36 and, hence, any desired degree of fineness of the ground material.

To a lug 37 on one side of the frame 1 there is attached, by means of a screw 38, a curved rail 39, the lower end of which is fork-shaped and passes through a recess 40, Figs. 3, 6 and 7, in the washer 32 provided between the quern case and one of the hand wheels 33.

The end of the recess 40 facing the rail 39 has a sloping bottom face 41, and the rail 39 is fitted with a corresponding sloping face 42, Fig. 3.

The quern described acts in the following manner: When the shaft 7 is rotated by means of the pulley 12, the grinding body 9 is thereby caused to rotate, and the eccentric sleeve 11 on said shaft moves the rod 17 up and down and, consequently, alternately lifts and lowers the shaking tray 15, thus causing the latter to oscillate about the pin 16. The material fed into the hopper 13 falls therefrom upon the shaking tray and, actuated by the motions of the tray, travels longitudinally through the said tray and drops down into the channel 6, whence it passes by way of the aperture 5 in the grinding body 4, to the grinding surfaces 35 and 36. After being ground the material leaves the quern by way of a discharge spout 43 on the side of the quern case, whence it is caught in a box 44 serving to store it and to support the post 1. The material may be directed from the spout 43 to the box 44 by any suitable means such as hose, a bottomless bag or the like, one end of which is joined to the spout 43 while the other end is inserted into the box 44 by way of an aperture (not shown) in the same.

The limits of the present invention will not be transgressed by omitting the box 44 and by discharging the material from the spout 43 into any other devices of known nature, such as bags, boxes, pails and the like.

As shown by Figs. 1 and 2 the quern case is split and its members joined together by means of screws 46. The grinding body 4 is attached to the quern case by means of a suitable number of screws 47 which are screwed either directly into the grinding body

4, provided that the latter is made of steel, or into a suitable cast-iron base on the grinding body, provided that said body is constructed of some stone-like or similar material.

When an overloading of the quern occurs, for instance by more grain being fed into the quern than the latter is able to grind, or by some foreign body penetrating between the grinding surfaces, then the friction produced between the material and the rotary grinding body, which friction reacts on the grinding body 4 fixed to the quern case, will cause the latter, when actuated by this friction, to rotate in a direction opposite the arrow in Fig. 2, whereby the spring 23 will be compressed.

This rotation will bring the sloping face 41 of the recess 40 in the washer 32 towards the sloping face 42 on the rail 39 which will cause the washer 32 and, hence, the bolt 31 and the end of the arm 39 connected thereto, to move in the direction indicated by the arrow in Figs. 1 and 3, whereby the central portion 28 of the arm 29 will force the ring 27 and, thereby, the shaft 7 and the grinding body 9 to move axially away from the grinding body 4. In this way the quern is unloaded.

When the cause of the overloading disappears, the spring 23 will return the quern case into the position shown in Fig. 2, and the spring 10 will then move the grinding body 9 back into the position corresponding to its original adjustment. Provided that the overloading is due to excessive filling of the quern channel with material it will be suitable, in case of overload, to reduce the supply of grain to the channel. This reduction is attained by the provision, on the periphery of the quern case, of a cam 49 (Fig. 2) the wedge-shaped face 50 of which projects down below a lug 51 on the under side of the shaking tray. When the quern case is rotated in consequence of an overload, the sloping face 50 of the cam 49 will strike the lug 51 from below and lift the shaking tray 15 so far that it will clear the top end of the rod 17, which latter cannot then actuate the shaking tray any more. The tray will therefore become stationary, and the passage of material along the tray and, consequently, the supply of material into the feeding channel will therefore be reduced very considerably.

On a boss 52 on the side of the quern case there is pivoted by means of a pin 53, Figs. 2 and 3, a lever comprising a handle portion 54 and a head or cam portion 55, the periphery of which rests against the frame 1. By rotation of the lever about the pin 53, in such a manner that the periphery of the cam 55 is forced to slide against the frame 1, the quern case may be turned by hand against the action of the spring 23, whereby the

grinding bodies are removed from one another in the above described manner.

It will be within the scope of the invention to mount the quern case in some other manner than described above, and to effect the adjustment of the grinding bodies relatively to one another and their displacement during overloading of the quern in a manner differing materially from the one described above.

10 Figs. 4 and 5 show for instance a construction of the present quern in which the frame of the quern case, instead of providing one single bearing for journaling the quern case, provides two bearings 60 and 61, respectively, serving to support the same. The quern case which, in this construction also, is mainly cylindrical, with a discharge spout 43 projecting from the periphery, is fitted, at both end faces, with trunnions 63, 64 journalled 20 each in one of the bearings 60 and 61, in such a manner that the quern case may rotate in said bearings. Any not intended rotation of the quern case is prevented by means of two springs 76 and 66, Fig. 5, which are each 25 pushed over an end of a lug 67 provided on the inner side of one of the bearings 61, and a stop 68 on the quern case in close proximity with the said lug. The outer end of each spring rests against the washer 69 which is 30 attached to the bolt ends by means of nuts 70, and the inner ends of the springs 76 and 66 bear against the stop 68 and the lug 67, respectively, suitable pressure blocks 71 being inserted between the latter and the 35 spring ends.

As appears from Fig. 5, the bore in the lug 67 through which the bolt 72 passes is flaring, so that said bolt may oscillate in the lug 67 when the quern case is rotated in the 40 direction indicated by the arrow in Fig. 5. The quern shaft 7 is journalled, in both of the trunnions 63 and 64, in ball bearings 65, one of which is provided in each of the said trunnions. The spring 10 pressing the rotary 45 grinding body against the material between the grinding surfaces is disposed inside of the trunnion 63 and encircles the portion of the shaft 7 which is situated between the grinding body 9 and the ball bearing 65 in the said trunnion.

The other end of the quern shaft projects 50 into the trunnion 64 and is supported there as mentioned above by a ball bearing 65, and the shaft itself supports the eccentric sleeve 55 11 serving to move the operating rod 17 of the shaking tray 15. The last mentioned end of the shaft 7 is further provided with a bore of suitable depth, and in this bore a ball 73 is inserted. This ball receives the pressure 60 from the end of a threaded spindle 74 which is screwed into a nut 75 and outside of the said nut supports a hand wheel 77. The nut 75 is fitted inside the outer end of the trunnion 64 and engages with diametrically opposite pins 78, a ring 80 encircling the outer

end of the trunnion 64 and pivoted on a pin 81 in the lug 82 on the bearing 61. The ring 80 is attached, at one point of its periphery, to the pin 64 by means of a screw 83. 84 is a wing nut serving as check-nut for the nut 75 and securing the spindle 74 immovably in the latter.

In this construction also, the shaking tray 15 is pivoted about a pin 16 on the feeding hopper 13, the supporting brackets 14 of 75 which are attached to the top part of the bearing 61. The supply opening or channel 6 is disposed immediately inside of the bearing 61. 85 is a tappet corresponding exactly to the cam member 50 in Fig. 2, but 80 is here attached to a collar 86 which limits the supply opening 6. The top face of the tappet 85 rests against a projection 51 on the bottom side of the shaking tray 15.

By loosening the nut 84 and turning the hand wheel 77, the shaft 7 may be displaced longitudinally against the action of the spring 10, whereby the grinding body 9 will be moved away from the grinding body 4, so that it will be practicable to adjust the 90 grinding bodies to any desired clearance.

An automatic adjustment of the load on the quern is effected in the following manner: If the quern is overloaded, for instance in consequence of too much material being introduced into the quern casing, then the latter will rotate in the direction indicated by the arrow in Fig. 5, and the springs 66 and 76 will thereby be compressed. Due to this rotation the pin 78 on the nut 75 will 100 move upward in the sloping slot 79, as indicated by the arrow in Fig. 4, and thereby the nut 75 and consequently the threaded spindle 74 will be pushed inward into the trunnion 64, in such a manner that the shaft 7 will be displaced and will pull the grinding body 9 away from the grinding body 4.

The rotation of the quern case will, at the same time, cause the tappet 85 to lift the shaking tray in such a manner that the latter ceases to be actuated by the rod 17 during the continued rotation of the shaft 7, whereby the supply of grain will be greatly reduced as mentioned above.

If preferred, there may be used, instead of the spring device comprising parts 66-72, a device like the one shown in Figs. 1-3 for preventing the rotation of the quern case, and in general the above described details of the first construction may be applied directly to the modified construction, without the scope of the invention being thereby exceeded.

In both constructions the quern case is journalled in the fixed frame of the quern, and the quern shaft is journalled in the quern case proper. It would be within the scope of the invention, however, to journal the quern case about the quern axle itself, as indicated diagrammatically in Fig. 8, and to 125

journal the shaft 7 in the bearings 90 on a base or bed 91, there being then inserted between the quern case 2 and the base 91 a resilient device 92 of any suitable construction preventing the rotation of the quern case until the load on the quern exceeds a certain permissible limit. In such case the rotation of the quern case will cause an axial displacement of the latter away from the rotary grinding body 9 as indicated by the arrow in Fig. 8. The spring 10 may be inserted, for instance, between a ring 93 fixed on the shaft 7 and the ring 27 resting against the central portion 28 (Fig. 1) of the arm 29. 15 In the construction shown in Fig. 8 the guiding rails 39 may be disposed at any suitable point of the quern base 91.

Having now particularly described and ascertained the nature of my said invention 20 and in what manner the same is to be performed, I declare that what I claim is:—

1. A quern comprising a quern shaft, a quern case arranged to revolve about the axis of the quern, a grinding body attached to 25 the quern case, a grinding body facing the first one and attached to the quern shaft to be rotated by the same, means to prevent rotation of the quern case until the load on the quern exceeds a permissible limit and to 30 allow the quern case to perform a rotary motion in the direction of motion of the quern shaft consequent upon the friction which, during an overload arises between the material to be ground and the grinding bodies, 35 and means whereby the quern case, on being rotated, spaces the grinding bodies from each other.

2. A quern comprising a quern shaft, a quern case arranged to revolve about the axis 40 of the quern, a grinding body attached to the quern case, a grinding body facing the first one and attached to the quern shaft to be rotated by the same, a feeding device disposed above a supply opening in the quern case, 45 means operated by the quern shaft during its rotation for oscillating the feeding device, means to prevent rotation of the quern case until the load on the quern exceeds a permissible limit and to allow the quern case 50 to perform a rotary motion in the direction of motion of the quern shaft consequent upon the friction which, during an overload, arises between the material to be ground and the grinding bodies, means whereby the quern case, on being rotated, spaces the grinding bodies from each other, and means 55 whereby the quern case simultaneously effects such a relative displacement between the feeding device and the means for oscillating it that the supply of material fed to the quern case will be reduced.

3. A quern comprising a quern case, a quern shaft journalled in the quern case, a frame in 60 which the quern case is journalled co-axially with the quern shaft, a grinding body at-

tached to the quern case, a grinding body facing the first one and attached to the quern shaft to be rotated by the same, a feeding device disposed above a supply opening in the quern case, means operated by the quern shaft during its rotation for oscillating the feeding device, means to prevent rotation of the quern case until the load on the quern exceeds a permissible limit and to allow the quern case to perform a rotary motion in the direction of motion of the quern shaft consequent upon the friction which, during an overload arises between the material to be ground and the grinding bodies, means whereby the quern case, on being rotated, spaces the grinding bodies from each other, and means whereby the quern case simultaneously effects such a relative displacement between the feeding means for oscillating it that the supply of material fed to the quern case will be reduced.

4. A quern comprising a quern case, a quern shaft journalled in the quern case, a frame in which the quern case is journalled co-axially with the quern shaft, a grinding body attached to the quern case, a grinding body facing the first one and attached to the quern shaft to be rotated by the same, a feeding device which is disposed above a supply opening in the quern case and directs material thereto, means for actuating said feeding device, means connecting the said frame to the quern case and preventing rotation of the latter until the load on the quern exceeds a permissible limit, said means allowing the quern case to perform a rotary motion in the direction of motion of the quern shaft consequent upon the friction which, during an overload, arises between the material to be ground and the grinding bodies, means whereby the quern case, on being rotated spaces the grinding bodies from one another, and means whereby the quern case simultaneously effects such a relative displacement between the feeding device and its actuating means that the supply of material fed to the quern case will be reduced.

5. A quern comprising a quern case, a quern shaft journalled in the quern case, a frame in which the latter is journalled, a grinding body attached in the quern case, a grinding body attached, opposite the first one, to the quern shaft to be rotated by the same, means for adjusting the distance between the grinding surfaces on the two grinding bodies, a feeding device which is disposed above a supply opening in the quern case and directs material thereto, means for actuating said feeding device, means connecting the said frame to the quern case and preventing rotation of the latter until the load on the quern exceeds a permissible limit, said means allowing the quern case to perform a rotary motion in the direction of motion of the quern shaft consequent upon the friction

which, during an overload, arises between the material to be ground and the grinding bodies, means whereby the quern case, on being rotated, spaces the grinding bodies from each other, and means whereby the quern case simultaneously effects such a relative displacement between the feeding device and its actuating means that the supply of material fed to the quern case will be reduced.

10. 6. A quern comprising a quern case, a quern shaft journalled in the quern case, a frame in which the quern case is journalled co-axially with the quern shaft, a grinding body attached to the quern case, a grinding body attached, opposite the first one, to the quern shaft to be rotated by the same, a spring maintaining the rotary grinding body pressed against the material to be ground between the grinding surfaces of the two bodies, means 15 for adjusting the distance between the two grinding surfaces against the pressure of the said spring, a feeding device which is disposed above a supply opening in the quern case and directs material thereto, means for 20 actuating said feeding device, means connecting the said frame to the quern case and preventing rotation of the quern case until the load on the quern exceeds a permissible limit, said means allowing the quern case to perform 25 a rotary motion in the direction of motion of the quern shaft consequent upon the friction which, during an overload, arises between the material to be ground and the grinding bodies, means whereby the quern case, on being rotated, spaces the grinding bodies from 30 each other, and means by which the quern case simultaneously effects such a relative displacement between the feeding device and its actuating means that the supply of material 35 fed to the quern case will be reduced.

7. A quern comprising a quern case, a quern shaft journalled in the quern case, a frame in which the quern case is journalled, resilient means connecting the quern case with the frame and preventing rotation of the quern case so long as the load on the quern does not exceed a certain limit, a grinding body fixed 45 in the quern case, a grinding body attached to the quern shaft to be rotated by the same, a spring maintaining the last mentioned grinding body pressed resiliently against the material to be ground, means to adjust the distance between the grinding surfaces against the pressure of the said spring, means 50 by which the quern case, when rotated, effects an increase of the distance between the grinding surfaces, a feeding device, means actuated by the quern shaft and imparting an oscillatory motion to the feeding device, 55 and a cam on the quern case which, during a rotation of the quern case, moves the feeding device away from its actuating means, whereby the supply of grain fed to the quern case will be reduced.

8. A quern comprising a quern case, a quern

shaft journalled in the quern case, a frame in which the quern case is journalled, resilient means connecting the quern case with the frame and preventing rotation of the quern case so long as the load on the quern does not exceed a certain limit, a grinding body which is attached to the quern case, a grinding body attached to the quern shaft and rotated by the same, a spring maintaining the last mentioned grinding body pressed resiliently against the material to be ground, means to adjust the distance between the grinding surfaces against the pressure of the said spring, said adjusting means being actuated by the quern case, when the latter rotates, in such a manner that the said means push one grinding body away from the other one, whereby the quern is relieved; a feeding device, means moved by the quern shaft and imparting an oscillatory motion to the feeding device, and a cam on the quern case which, during a rotation of the quern case, moves the feeding device away from its actuating means, whereby the supply of grain fed to the quern case will be reduced.

9. A quern comprising a quern case, a quern shaft journalled in the quern case, a frame in which the quern case is journalled, resilient means connecting the quern case to the frame and counteracting a rotation of said case, a grinding body which is attached to the quern case, a grinding body attached to the quern shaft and rotated by the same, a spring which maintains the rotary grinding body pressed resiliently against the material to be ground between the grinding surfaces, a body attached adjustably to the quern case and serving to transmit the pressure of the said spring to the quern shaft, a stop for the said body provided on the frame of the quern case; said body and said stop having coacting sloping contact surfaces to cause the said body and, hence, the quern shaft and the grinding body attached thereto to move axially when the quern case, by its rotation, moves the said body along the said stop; a feeding device, means actuated by the quern shaft for imparting an oscillatory motion to the feeding device, and a cam on the quern case which, when the latter is rotated in the direction of rotation of the quern shaft, pushes the feeding device away from the means serving to oscillate it, whereby the supply of grain fed to the quern case will be reduced.

10. A quern comprising a quern case, a quern shaft journalled in the quern case, a frame in which the quern case is journalled, resilient means connecting the quern case to the frame and counteracting a rotation of said case, a grinding body which is attached to the quern case, a grinding body attached to the quern shaft and rotated by the same, a spring which maintains the rotary grinding body pressed resiliently against the material to be ground between the grinding surfaces,

5 a body attached adjustably to the quern case and serving to transmit the pressure of the said spring to the quern shaft, a stop for the said body provided on the frame of the quern case; said body and said stop having coacting sloping surfaces to cause the said body and, hence, the quern shaft and the grinding body attached thereto to move axially when the quern case, by its rotation, moves the said 10 body along the said stop; a feeding device, means actuated by the quern shaft for imparting an oscillatory motion to the feeding device, a cam on the quern case which, when the latter is rotated in the direction of rotation of the quern shaft, pushes the feeding device away from the means serving to oscillate it, whereby the supply of grain fed to the quern case will be reduced, and an arm pivoted to the quern case, one end of said 15 20 arm resting against the frame of the quern case in such a manner that the arm, when rotated, forces the quern case to rotate in the frame, whereby the grinding bodies are moved away from each other.

25 11. A quern comprising a quern case, a quern shaft journalled in the quern case, a frame in which the quern case is journalled, resilient means connecting the quern case to the frame and counteracting a rotation of the 30 said case, a grinding body which is attached to the quern case, a grinding body attached to the quern shaft and rotated by the same, a spring which maintains the rotary grinding body pressed resiliently against the material

35 to be ground between the grinding surfaces, a body attached adjustably to the quern case and serving to transmit the pressure of the said spring to the quern shaft, a stop for the said body provided on the frame of the quern case; said body and said stop having coacting sloping contact surfaces to cause the said body and, hence, the quern shaft and the grinding body attached thereto to move axially when the quern case, by its rotation, moves the said 40 45 body along the said stop, a box to receive the ground material and to support the frame, a feeding device, means actuated by the quern shaft for imparting an oscillatory motion to the feeding device, a cam on the quern case which, when the latter is rotated in the direction of rotation of the quern shaft pushes the feeding device away from the means serving to oscillate it, whereby the supply of grain fed to the quern case will be reduced, and an arm pivoted to the quern case, one end of said arm resting against the frame of the quern case in such a manner that the arm, when rotated, forces the quern case to rotate in the frame, whereby the grinding bodies are 50 55 60 moved away from each other.

65 12. A quern comprising a quern case, a trunnion on one side of the quern case, a post in which the said trunnion is journalled, a spring connecting the post to the quern case and counteracting a rotation of the latter, a

quern shaft journalled in the said trunnion and projecting into the quern case, a grinding body attached to the quern shaft inside of the quern case, a grinding body attached to the quern case and facing the first mentioned grinding body, a shoulder on the quern shaft, an adjustable arm provided on the quern case, a spring provided in the trunnion on the quern case and encircling the quern shaft and adapted to exert an axial resilient pressure which maintains said shoulder in contact with said adjustable arm, so that an adjustment of said arm causes the quern shaft to be displaced axially, whereby the space between the grinding bodies is varied, a stop attached to the said post and resting against one end of the said arm, means whereby the other end of the said arm may be adjusted manually relatively to the quern case and thereby caused to move in such a manner that it displaces the quern shaft axially, a shaking tray pivoted to the frame and set into oscillating motion by action of the quern shaft, a cam on the periphery of the quern case adapted to push the shaking tray away from the members actuating the same when the quern case is rotated, and an arm pivoted to the quern case and having one end resting against the post, in such a manner that on rotation of the arm, its said end forces the pivot of the arm on the quern case to move away from the post and, consequently, the quern case to rotate.

In testimony whereof he affixes his signature.
